(57) **CLAIM**

The ornamental design for a tire, as shown and described.

DESCRIPTION

FIG. 1 is a perspective view of the tire of my design; FIG. 2 is a front elevation view of the tire of my design; FIG. 3 is a side elevation view of the tire of my design; FIG. 4 is a side elevation view of the tire of my design, taken from the opposite side of that shown in FIG. 3; and, FIG. 5 is an enlarged, partial view of the tire of FIG. 1, as indicated by the break lines.

The broken line disclosure in the drawings depicts environmental subject matter forming no part of the claimed design. The dash-dot-dot-dash lines define the peripheral boundaries of the claim. The tread pattern repeats over the circumference of the tire.
